RECLINING ARTICLE OF FURNITURE

Anton Lorenz, Buffalo, N.Y.

Application December 29, 1945, Serial No. 637,936

11 Claims. (Cl. 155—106)

1

This invention relates to an article of furniture, and more particularly to a reclining article of furniture, wherein the back-rest and seat form movable members of a polygonal link-system swingably mounted on a support and wherein the movements of the members of said polygonal link-system are positively controlled by a guiding link pivoted to the support and operatively connected with a member of the polygonal link-system.

An object of the present invention is to provide a convenient controlling mechanism for a leg-rest swingably mounted on the seat of a reclining article of furniture of above described type, by means of which the angle between the leg-rest and the seat is automatically altered in dependence on the movements of the guiding link when the movable members of the reclining article of furniture including the back-rest and the seat are brought from a certain position, such as the sitting position, into another position, such as a reclined position, or vice versa.

A further object of the present invention is to equip a reclining article of furniture of above described type with a controlling mechanism for the leg-rest, which may cause a movement of the leg-rest relative to the seat, when the position of the polygonal link-system is altered, which, however, does not form a positive connection between the leg-rest and the controlling mechanism and permits an independent movement of the leg-rest relative to the seat, when the members of the polygonal link-system are held in a certain position relative to each other.

Still another object of the present invention is to provide a support for a reclining article of furniture of above described type, which renders the controlling mechanism for the leg-rest invisible when the members of the article of furniture are in the sitting position, and which permits a ready mounting of the elements of said controlling mechanism swingably arranged on the support.

A further object of the present invention is to improve on reclining articles of furniture of above described type as now ordinarily made.

With the above and other objects of the invention in view, the invention consists in the novel construction, arrangement and combination of various devices, elements and parts, as set forth in the claims hereof, certain embodiments of the same being described in the specification and being illustrated in the accompanying drawings forming part of this specification, wherein:

Fig. 1 is a side elevational view of a reclining chaise longue equipped with a controlling mechanism for the leg-rest according to the invention.

2

Fig. 2 is a fragmentary perspective view of a part of the controlling mechanism for the leg-rest of the chaise longue shown in Fig. 1.

Fig. 3 is a sectional view of the locking device of the chaise longue shown in Fig. 1, taken on line 3—3 of Fig. 1.

Fig. 4 is a side elevational view of a reclining chair equipped with another embodiment of a controlling mechanism of the leg-rest, according to the invention.

Fig. 5 is a side elevational view of another embodiment of a reclining chair according to the invention, a portion of a side wall being broken away so as to illustrate the controlling mechanism for the leg-rest.

Fig. 6 is a fragmentary view of an adjustable portion of the controlling mechanism for the leg-rest of the chair shown in Fig. 5, said view being taken on line 6—6 of Fig. 5.

Fig. 7 is a perspective view of the support of the chair shown in Fig. 5 with a portion of the controlling mechanism of the leg-rest mounted therein.

Fig. 8 is a fragmentary view of a safety device 25 for holding the swingable portion of the controlling mechanism for the leg-rest in position in the support shown in Fig. 7.

Fig. 9 is a side elevational view of still another embodiment of a reclining chair according to the invention.

Fig. 10 is a side elevational view of a foldable and convertible reclining chaise longue, according to the invention equipped with a different embodiment of a controlling mechanism for the leg-rest.

Fig. 11 is a side elevational view of a reclining wheel chair according to the invention equipped with another embodiment of a controlling mechanism for the leg-rest.

Fig. 12 is a fragmentary side elevational view of the holding device for the leg-rest of the wheel chair shown in Fig. 11, on an enlarged scale.

Fig. 13 is a sectional view of the holding device taken on line 13—13 of Fig. 12.

Figs. 14—16 are perspective views of three different embodiments of a controlling unit of the chair shown in Figs. 5 and 7, and

Fig. 17 is a fragmentary side elevational view of the front portion of a chair according to the invention, illustrating a different embodiment of the controlling mechanism for the leg-rest.

Referring now to Fig. 1, 20 generally indicates the support of an article of furniture known in the trade as a chaise longue or lounger. The support made of tubular material is reinforced by

the bracing members 22 of tubular material. The chaise longue may be moved along the ground by means of wheels 24 journalled in suitable bearings arranged at the rear portion of the support 20.

26 generally indicates a back-rest and 28 indicates a seat, the rear end of which is pivoted to said back-rest and the support 20 at 30. A link-mechanism including a pair of connecting links 32 and 34 is arranged on each side of the chaise longue. The connecting link 32 of said pair of connecting links may be called a top connecting link, which forms an arm-rest, the connecting link 34 of said pair of connecting links will be designated hereinafter as a front connecting link. The top connecting link 32 and the front connecting link 34 are pivotally connected with each other at 36. The rear end of each top connecting link is pivoted at 38 to an intermediate point of the back-rest 26 above the seat 28. The lower end of each front connecting link 34 is pivoted to the front portion of the seat 28 at 40. The pivotally interconnected back-rest 26, seat 28, and link mechanism 34, 32 form the movable members of a constrained kinematic polygonal link-system in the shape of a quadrilateral link-system, which is swingably mounted on the support 20 at the pivot point 30 between the back-rest 26 and the seat 28 for movement about a single axis. A guiding link 42 is arranged on each side of the chaise longue for controlling the movements of the movable members 26, 28, 34, 32 of the quadrilateral link-system. The lower end of each guiding link 42 is rigidly connected with a transverse rod 44 (see Figs. 1 and 2) journalled in suitable bearings of the support 20. The upper end of each guiding link 42 is pivotally connected with the link-mechanism 32, 34 at the pivot point 36 between the top connecting link 32 and the front connecting link 34.

According to Fig. 1, the seat 28 rests on one of the bracing members 22 of the support 20 when it occupies its horizontal sitting position shown in full lines.

A leg-rest 46 is pivotally connected with the front portion of the seat 28 at 48. One end of a controlling element or controlling bar 50 is positively connected with the guiding link 42 by a rigid connection with the rotatable transverse rod 44, so that said controlling bar 50 will be moved simultaneously with the guiding link 42. The other end of said controlling bar 50 is pivoted to one end of a telescopic controlling link generally indicated by 52 at 54. The other end of said telescopic controlling link 52 is pivoted at 56 to a lug 58 mounted on the leg-rest 46. The telescopic controlling link 52 comprises the telescopically arranged members 60 and 62, and the effective length of the telescopic controlling link 52 may be adjusted by means of the set screw 64. As will be readily understood, the controlling element 50 positively connected with the guiding link 42 and operatively connected with the leg-rest 46 through the medium of the controlling link 52 controls the movements of the leg-rest 46 in dependence on the movements of the guiding link 42.

When the occupant resting in the chaise longue leans the weight of his body against the back-rest, the movable members of the polygonal link-system are brought into a reclined position shown in dash and dot lines in Fig. 1, wherein the back-rest and the seat are in the position 26' and 28' respectively. Said extreme reclined position is limited by a stop 66 mounted on the support 20 for cooperation with the back-rest. During such

a movement of the movable members of the polygonal link-system controlled by the guiding link being moved from the position 42 into the position 42', the leg-rest is brought from the position 46 into the position 46' by means of the controlling bar 50 and controlling link 52.

The back-rest, seat, and leg-rest may be held in any desired position, for example in the extreme reclined position 26', 28', 46', or in any other intermediate reclined position by means of a locking device generally indicated by 68 and arranged on the pivot 38 connecting the top connecting link 32 with the back-rest 26. As best shown in Figs. 1 and 3, said locking device 68 comprises a handle 70 screwed on the threaded end of the pivot 38. Said pivot 38 has a head 72 resting against the surface of the back-rest 26. A square portion 74 of the pivot 38 is inserted into a corresponding square aperture of the back-rest 26, whereby the pivot 38 is prevented from rotation. When the user of the chaise longue loosens the locking handle 70, the surface of the hub 76 of said handle is disengaged from the surface of the top connecting link 32, so that the movable members of the chaise longue may be freely moved from one position into another one. When the locking handle 70 is tightened, the surface of the hub of the handle is pressed against the top connecting link 32, whereby the latter is pressed against the back-rest 26 engaged with the head 72 of the pivot 38, so that the members of the chaise longue are held in their position. Of course, any other type of locking device may be used instead of said locking device 68, if desired.

Under certain conditions it may be desirable to change the position of the leg-rest 46 relative to the position of the seat 28. For example, it may be desirable to bring the leg-rest 46 into the position 46'' in alignment with the seat 28, when the latter is in the sitting position. For this purpose, the effective length of the telescopic controlling link 52 is enlarged, so that the telescopic controlling link occupies the position 52''. When said enlarged length of the controlling link is fixed by the set screw 64, and when the movable back-rest and seat of the lounger are moved into the extreme reclined position 26', 28', the leg-rest is brought from the position 46'' into the position 46'''.

According to the embodiment of a reclining chair shown in Fig. 4, the quadrilateral link-system 126, 128, 134, 132 is swingably mounted on lugs 178 of the support 120 at 130. The movements of said quadrilateral link-system are controlled by a guiding link 142 pivoted to a lug 180 of the support 120 at 144 and pivoted to the top connecting link 132 at 137. The controlling element or controlling bar 150 arranged for the controlling of the leg-rest 146 swingably mounted at 148 on the seat 128 is integral with the guiding link 142 and may be considered as a lower extension of the latter. Of course, the positive connection between the controlling bar 150 and the guiding link 142 could also be formed by a rigid connection of two separate elements by means of screws. One end of the controlling link 152 is pivoted to the controlling bar 150 at 154, and the other end of said controlling link 152 is pivoted to the leg-rest 146 at 156.

When the back-rest 126 is swung about its pivot 130, the movable members of the chair may be brought from the sitting position shown in full lines and limited by the transverse rod 122 of the support 120 into the extreme reclined position

shown in dash and dot lines and limited by the stop 166 of the support 120. The movable members of the chair may be held in any desired position by means of the locking device 168 corresponding to the locking device shown in Fig. 3.

The top connecting link 132, the front connecting link 134, the guiding link 142, the leg-rest 146, the controlling bar 150, and the controlling link 152 are provided with series of holes 182. Each of the pivots 136, 137, 140, 144, 154, 156 may be selectively engaged with one of said holes 182, whereby the effective length of the various members of the chair may be altered for a different arrangement of some of the members of the chair relative to each other and for different relative movements between some of the members of the chair.

According to the embodiment shown in Fig. 5, the support is in the shape of a casing generally indicated by 220. Said casing comprises the side walls 221 and 223 and the front wall 225 and the rear wall 227 (see Figs. 5 and 7).

The rear end of the seat 228 is pivoted to the support 220 at 230, and the lower end of the back-rest 226 is pivoted to said support at the point 231 spaced from the pivotal connection 230 between the seat and the support. On each side of the chair, the rear end of the top connecting link 232 is pivoted to an intermediate point of the back-rest 226 at 238. The other end of said top connecting link 232 is pivoted at 235 to one end of an intermediate connecting link 284. The other end of said intermediate connecting link 284 is pivoted at 239 to the upper end of the front connecting link 234, the lower end of which is pivoted to the seat 228 at 240. Thus, the movable back-rest 226, the movable link-mechanism 232, 284, 234, the movable seat 228 and the stationary portion of the support 220 between the pivotal connections 230 and 231 of the seat 228 and the back-rest 226 with the support 220 form the members of a hexagonal link-system. On each side of the chair the guiding link 242 is integral with the intermediate connecting link 284, whereby the guiding link is operatively connected at its upper end with said intermediate connecting link. If desired, the guiding link and the intermediate connecting link could be in the shape of two separate members rigidly connected with each other by screws or the like. The lower end of each guiding link 242 is rigidly secured to a transverse rod 244 rotatably arranged in recesses 286 of the walls 221 and 223 of the support 220 (see Figs. 7 and 8). The recesses 286 are open at the top and the transverse rod 244 is held in its position by means of safety members 288 attached to the side walls of the support 220 by screws. One end of a controlling element or controlling bar 250 is rigidly secured to the transverse rod 244, so that the two guide bars 242 and the transverse rod 244, and the controlling bar 250 form a unit generally indicated by 210. An adjusting element or bar 290 (see Figs. 5 and 6) is swingably mounted at 292 at the other end of the controlling bar 250. A stop 294 secured to the controlling bar 250 by screws is arranged for engagement with the swingable adjusting bar 290, so as to hold same in alignment with the controlling bar 250 as shown in full lines in Fig. 5. One end of the controlling link 252 is pivoted to said swingable adjusting bar 290 at 255, the other end of said controlling link 252 is pivoted at 256 to the leg-rest 246, swingably mounted on the seat 228 at 248. The controlling link 252 passes through a slot 296 in the front wall 225 of the support 220.

The sitting position of the members of the chair shown in full lines in Fig. 5 is limited by the upper edge of the support 220 on which the seat 228 comes to a rest.

When the back-rest 226 is swung about its pivot 231, the back-rest, seat, and leg-rest may be brought into the extreme reclined position 226', 228', 246' limited by an abutment of the back-rest against the stop 266.

The movable members of the chair may be held in any desired position by means of the locking device 268.

As mentioned above, the adjusting bar 290 is swingable about the pivot 292. If the back-rest and seat are held in a predetermined position, for example the sitting position shown in full lines in Fig. 5, by means of the locking device 268, the leg-rest 246 may be swung by hand about its pivot 248 into the position 246'', wherein the controlling link and the adjusting bar are in the positions 252'' and 290'' in alignment with each other. Now, when a slight pressure is exerted on the leg-rest, for example by the legs of the occupant resting in the chair, the controlling link 25 and the adjusting bar are moved slightly beyond said straight line, until a stop 298 secured to the adjusting bar 290 by screws abuts against the controlling link, whereby said elements are locked and held in a predetermined position relative to each other.

As will be readily understood, the support 220 is of such a construction, that the controlling mechanism 250, 290, 252 for the leg-rest is invisible, when the members of the chair are in the sitting position. Furthermore, the construction of the support permits an easy mounting of the controlling mechanism. The controlling unit 210 may be mounted on the support 220 by inserting its transverse rod 244 from above into the recesses 286 open at the top, whereupon the safety elements 288 are attached to the support 220 for holding said controlling unit in its place.

Fig. 14 illustrates a different embodiment of a controlling unit 210b, which may be substituted for the controlling unit 210 in the mechanism of the reclining chair shown in Figs. 5 and 7. According to Fig. 14, the controlling unit 210b comprises a U-shaped member 211b. The base of said U-shaped member 211b forms a transverse rod for swingable mounting in the recesses 286 of the support 220. The arms of said U-shaped member form the guiding links. To controlling bars 250b are rigidly secured to the base of the U-shaped member 211b. Of course, when such a controlling unit 210b with two arms 250b is used, two controlling links are interposed between said arms and the leg-rest 246. Furthermore, the front wall 225 of the support may be provided with two slots for the passage of said two controlling bars and said two controlling links instead of with one slot as shown in the drawings.

Fig. 15 illustrates another embodiment of such a controlling unit for swingable mounting in a support, which may be used in the mechanism of the chair shown in Figs. 5 and 7. The controlling unit 210c shown in Fig. 15 comprises three members 209c, 211c, and 213c rigidly connected with each other by rivets 212c or the like. Said members 209c, 211c, and 213c are shaped in such a way, that they form the guiding links and two controlling arms.

Likewise, the controlling unit 210d shown in Fig. 16 may be swingably mounted in the support of the chair shown in Figs. 5 and 7. The controlling unit 210d is composed of two members

209d; 213d rigidly connected by rivets 212d or the like. Said members are shaped in such a way, that they form the guiding links and a single controlling arm.

According to the embodiment of a reclining chair shown in Fig. 9 the rear end of the seat 328 is pivoted at 330 to a support 320 in the shape of a casing. The lower end of the back-rest 326 is pivoted to said support 320 at the point 331 spaced from the pivotal connection 330 between the seat and the support. The rear end of the top connecting link 332 is pivoted to an intermediate point of the back-rest 326 at 338. The other end of said top connecting link 332 is pivoted to the upper ends of the front connecting link 334 at 336. The lower end of said front connecting link 334 is pivoted to the seat 328 at 340. Thus, the movable back-rest 326, the movable link-mechanism 332, 334, the movable seat 328 and the stationary portion of the support 320 between the pivotal connections 330 and 331 of the seat 328 and the back-rest 326 with the support 320 form the members of a quinquelateral link-system. The upper end of a guiding link 342 is pivoted to the top connecting link 332 at 337, and the lower end of said guiding link 342 is pivoted to the support 320 at 344. The controlling bar 350 being integral with the guiding link 342 participates in any movement of the latter.

The leg-rest 346 swingably mounted at 348 on the seat 328 has an extension 300 projecting upwardly beyond the pivot 348. One end of the controlling link 352 is pivoted to the controlling bar 350 at 354, the other end of said controlling link 352 is pivoted to the extension 300 of the leg-rest 346 at 357.

The guiding link 342 controls the movements of the movable members 326, 328, 334, 332 of the polygonal link-system in the shape of a quinquelateral link-system, and furthermore said guiding link 342 controls the movements of the leg-rest 346 through the medium of the controlling bar 350 and the controlling link 352.

The sitting position shown in full lines is limited by the upper edge of the support 320, and the extreme reclined position shown in dash and dot lines is limited by the stop 366. The movable members of the chair may be held in any desired position by means of the locking device 368.

Fig. 10 illustrates a chaise lounge with a polygonal link-system or quadrilateral link-system of the type shown in Fig. 1. The seat 428 is pivoted to the back-rest 426 and lugs 478 of the support 420 at 430. The upper end of the guiding link 442 is pivoted to the top connecting link 432 and the front connecting link 434 at 436. The rear end of the top connecting link 432 is pivoted to the back-rest 426 at 438, the lower end of the front connecting link 434 is pivoted to the seat 440. The lower end of the guiding link is pivoted to the support 420 at 444.

One end of the controlling element 450 is rigidly connected with the guiding link 442 for a simultaneous movement with the latter. The other end of said controlling element 450 bears a roller 402 for shiftable engagement with the leg-rest 446 swingably mounted on the seat 428 at 448. The circumferential surface of the roller 402 constitutes a controlling or abutting surface 65 cooperating with an abutting surface on the lower side of the leg-rest 446.

The sitting position of the members of the chaise lounge shown in full lines is limited by an engagement of the seat 428 with the support 70

420, and the extreme reclined position of the members of the chaise lounge shown in dash and dot lines is limited by a stop 467 mounted on the support for engagement with the guiding link 442.

The members of the chaise lounge may be held in any desired position by means of a locking device 468 mounted on the pivot 440. The locking device 468 may be of the type shown in Fig. 3.

When the members of the chaise lounge are moved from one position into another one, the roller 402 of the controlling element 450 swung together with the guiding link 442 rolls along the surface of the leg-rest 446 and controls the movements of the latter, so that the leg-rest is, for example, in the position 446' when the back-rest and the seat are in the extreme reclined position 426' and 468' respectively.

Under certain circumstances it may be desirable to have the leg-rest in a different position relative to the seat when the latter is in a reclined position. For example it may be desirable to have the leg-rest in the position 446'' when the seat is in the extreme reclined position 428'. For this purpose, the controlling element 450 is of the telescopic type, and when the length of the telescopic controlling element 450 is set for having the roller in the position 402'' when the members of the chair are in the sitting position, the leg-rest will be brought into the position 446'' in alignment with the seat, when the latter is in its extreme reclined position 428'.

Of course, if desired, the roller 402 could be replaced by any suitable controlling surface on the controlling element 450 for slideable and shiftable engagement with the leg-rest 446.

At least one pivot of the polygonal link-system of the chaise lounge shown in Fig. 10 is disengageable; for example, the pivot 438 is disengageable. If said pivot 438 is removed, the back-rest 426 may be swung independently of the seat into the position 426''' limited by its abutment against the surface of the support 420. The seat 428 and the leg-rest 446 will be held in the substantially horizontal position shown in full lines in Fig. 10, substantially in alignment with the back-rest in its position 426'''.

Furthermore, the legs 404 of the support 420 are swingably mounted at 405 on the top member 406 of the support 420, so that they may be folded on the top member. The legs 404 are held in the supporting position shown in Fig. 10 by stops (not shown).

Fig. 11 illustrates a wheel chair having a support 520 provided with wheels 524 in any suitable manner. The polygonal link-system of said wheel chair corresponds to the polygonal link-system shown in Fig. 1. The seat 528 and the back-rest 526 are pivoted to lugs 518 of the support 520 at 530. The upper end of the guiding link 542 is pivoted to the top connecting link 532 and front connecting link 534 at 536. The lower end of said guiding link is pivoted to a lug 580 of the support 520 at 544. The rear end of the top connecting link 532 is pivoted to the back-rest 526 at 538, the lower end of the front connecting link 534 is pivoted to the seat 528 at 540. The leg-rest 546 is swingably mounted on the seat at 548.

One end of the controlling bar 550 is positively connected with the guiding link 542 for simultaneous movement with the latter. One end of a first controlling link 551 is pivoted to the other end of said controlling bar 550 at 554. The other end of said first controlling link is pivoted to one

end of a second controlling link 553 at 559. The other end of said second controlling link 553 is pivoted to the seat 528 at the pivot point 548 between the seat and the leg-rest. The second controlling link 553 is provided with a controlling surface 508 of cam-like shape (see Figs. 11 and 12). Said controlling surface 508 is arranged for loose contact with the leg-rest 546, which may be held against said controlling surface by means of a spring (not shown). When the leg-rest is in contact with said controlling cam surface 508, the movements of the leg-rest are controlled by the guiding link 542 through the medium of the controlling bar 550, the controlling link mechanism 551, 553, and the controlling surface 508. Thus, when the back-rest 526 is swung about its pivot 530, the back-rest and the seat may be swung into the reclined position 526', 528', and the leg-rest will be brought into the position 546' shown in dash and dot lines.

The sitting position shown in full lines is limited by the stop 507 of the support 520, and the extreme reclined position shown in dash and dot lines is limited by the stop 566 of the support.

The movable members of the chair may be held in any desired position by means of the locking device 568.

If desired, the leg-rest 546 may be moved independently of the second controlling link 553 relative to the seat 528, as the leg-rest 546 is in loose engagement with the controlling surface 508. For example, the leg-rest 546 may be brought into the position 546a, while the other members of the wheel-chair remain in the position shown in full lines. The leg-rest may be held in said position 546a by means of a holding device generally indicated by 541. As best shown in Figs. 12 and 13, said holding device 541 comprises a rod 543 slidably arranged in a clamping sleeve 545 engaged with a bolt 547 inserted with its square portion 549 into a square aperture of a lug 561 mounted on the seat 528. An adjusting knob 563 is threaded on the threaded end portion of the bolt 547 projecting from the clamping sleeve 545. When the adjusting knob 563 is loosened, the rod 543 may be displaced for engagement with the leg-rest in its elevated position 546a. Upon a tightening of the adjusting knob 563, the clamping sleeve 545 is tightened on the rod 543 for holding same and the leg-rest in its position. When the movable members of the chair are brought from the sitting position into a reclined position, the leg-rest will remain in the adjusted position relative to the seat until the controlling cam 508 of the second controlling link 553 abuts against the leg-rest 546, whereupon the controlling cam 508 controls the movements of the leg-rest and displaces same relative to the seat.

Fig. 17 illustrates a different embodiment of a control of the leg-rest 546, which may be substituted for the leg-rest control shown in Figs. 11 and 12. According to Fig. 17, the first controlling link 551 pivoted at 559 to the second controlling link 553 is provided with a cam-like controlling surface 508e in loose contact with the leg-rest pivoted to the seat 528 at 548 for controlling the movements of the leg-rest. Of course, the leg-rest 546 may be disengaged from said controlling surface 508e and may be held in a predetermined position relative to the seat 528 by the holding device 541.

It is understood that certain parts, elements, or mechanisms shown in a certain figure may

be substituted for corresponding parts, elements, or mechanisms of the embodiments shown in other figures of the drawings.

I have described preferred embodiments of my invention, but it is understood that this disclosure is for the purpose of illustration, and that various omissions or changes in shape, proportion, and arrangement of parts, as well as the substitution of equivalent elements for those herein shown and described, may be made without departing from the spirit and scope of the invention as set forth in the appended claims.

What I claim is:

1. An article of repose for supporting the body of a person, comprising in combination: a support, a constrained linkage having stationary link means and a plurality of movable links, said stationary link means being included in said support, said movable links including a seat member, a back rest member, a guiding link and a chain of connecting links including a top connecting link at one end of the chain and a front connecting link at the other end of the chain, at least one of said connecting links being arranged above the plane of the seat member, the lower end of said guiding link being pivoted to said support, the upper end of said guiding link being connected with at least one of said connecting links, said top connecting link being pivoted to an intermediate point of the back rest member, said front connecting link being pivoted to the front portion of said seat member, means pivotally connecting at least one of said back rest and seat members with said support, a leg rest swingably mounted on the front portion of said seat member, a controlling member fixedly connected to said guiding link, and means, interposed between said controlling member and said leg rest, for effecting movement of the latter in coordination with said controlling member.

2. In an article of repose as claimed in claim 1, a transverse rod journalled in said support, said guiding link and said controlling member being rigidly connected with said transverse rod.

3. An article of repose for supporting the body of a person, comprising in combination: a support, a constrained linkage having stationary link means and a plurality of movable links, said stationary link means being included in said support, said movable links including a seat member, a back rest member, a guiding link and a chain of connecting links including a top connecting link at one end of the chain and a front connecting link at the other end of the chain, at least one of said connecting links being arranged above the plane of the seat member, the lower end of said guiding link being pivoted to said support, the upper end of said guiding link being connected with at least one of said connecting links, said top connecting link being pivoted to an intermediate point of the back rest member, said front connecting link being pivoted to the front portion of said seat member, means pivotally connecting at least one of said back rest and seat members with said support, a leg rest swingably mounted on the front portion of said seat member, a controlling member fixedly connected to said guiding link, and a controlling link, one end portion of said controlling link being pivoted to said controlling member, the other end portion of said controlling link being pivoted to said leg rest.

4. In an article of repose as claimed in claim 3, said controlling link being of adjustable length,

and means for adjusting a predetermined length of said controlling link.

5. An article of repose for supporting the body of a person, comprising in combination: a support, a constrained linkage having stationary link means and a plurality of movable links, said stationary link means being included in said support, said movable links including a seat member, a back rest member, a guiding link and a chain of connecting links including a top connecting link at one end of the chain and a front connecting link at the other end of the chain, at least one of said connecting links being arranged above the plane of the seat member, the lower end of said guiding link being pivoted to said support, the upper end of said guiding link being connected with at least one of said connecting links, said top connecting link being pivoted to an intermediate point of the back rest member, said front connecting link being pivoted to the front portion of said seat member, means pivotally connecting at least one of said back rest and seat members with said support, a leg rest swingably mounted on the front portion of said seat member, a controlling member fixedly connected to said guiding link, an adjusting bar swingably mounted on said controlling member, a controlling link pivoted at one of its ends to said adjusting bar and at its other end to said leg rest, and means associated with said controlling member and said adjusting bar for holding the latter in one predetermined position relative to said controlling member.

6. In an article of repose as claimed in claim 5, means associated with said adjusting bar and said controlling link for holding said adjusting bar in one predetermined position relative to said controlling link.

7. An article for repose for supporting the body of a person, comprising in combination: a support, a constrained linkage having stationary link means and a plurality of movable links, said stationary link means being included in said support, said movable links including a seat member, a back rest member, a guiding link and a chain of connecting links including a top connecting link at one end of the chain and a front connecting link at the other end of the chain, at least one of said connecting links being arranged above the plane of the seat member, the lower end of said guiding link being pivoted to said support, the upper end of said guiding link being connected with at least one of said connecting links, said top connecting link being pivoted to an intermediate point of the back rest member, said front connecting link being pivoted to the front portion of said seat member, means pivotally connecting at least one of said back rest and seat members with said support, a leg rest swingably mounted on the front portion of said seat member, a controlling member fixedly connected to said guiding link, said controlling member extending upwardly above the plane of the seat, said leg rest having an extension projecting upwardly beyond its connection with the seat member, and a controlling link arranged above the plane of the seat member, one end portion of said controlling link being pivoted to said controlling member, the other end portion of said controlling link being pivoted to said extension of the leg rest.

8. An article of repose for supporting the body of a person, comprising in combination: a support, a constrained linkage having a stationary link means and a plurality of movable links, said stationary link means being included in said support, said movable links including a seat member, a back rest member, a guiding link and a chain of connecting links including a top connecting link at one end of the chain and a front connecting link at the other end of the chain, at least one of said connecting links being arranged above the plane of the seat member, the lower end of said guiding link being pivoted to said support, the upper end of said guiding link being connected with at least one of said connecting links, said top connecting link being pivoted to an intermediate point of the back rest member, said front connecting link being pivoted to the front portion of said seat member, means pivotally connecting at least one of said back rest and seat members with said support, a leg rest swingably mounted on the front portion of said seat member, a controlling member fixedly connected to said guiding link, a first controlling link pivoted at one of its ends to said controlling member, a second controlling link pivoted at one of its ends to the other end of said first controlling link and pivoted at its other end to the front portion of said seat member, and cooperating abutting surfaces arranged on the structure of one of said controlling links and on the structure of said leg rest for controlling the movements of said leg rest in dependence on the movement of the movable links of said constrained linkage, said cooperating abutting surfaces loosely abutting against each other whereby said abutting surfaces may be disengaged from each other for the performance of independent movements of the leg rest relative to the seat member.

9. In an article of repose as claimed in claim 8, a holding device connected with said seat member for cooperation with said leg rest so as to hold the latter in a predetermined position relative to the seat member during disengagement of the abutting surfaces from each other.

10. An article of repose as claimed in claim 8, wherein one of said abutting surfaces is arranged on the structure of said first controlling link.

11. An article of repose as claimed in claim 8, wherein one of said abutting surfaces is arranged on the structure of said second controlling link.

ANTON LORENZ.
